UNITED STATES PATENT OFFICE

ERNEST A. WEEKS, OF KALAMAZOO, MICHIGAN, ASSIGNOR TO ROOT SPRING SCRAPER COMPANY, OF KALAMAZOO, MICHIGAN

ROAD SCRAPER

Application filed January 11, 1928. Serial No. 245,982.

This invention relates to improvements in road scrapers.

The objects of the invention are:

First, to provide hydraulic control for a road scraper.

Second, to provide such a structure which is self-contained as an attachment for a truck.

Third, to provide such a structure which will utilize hydraulic pressure means provided for controlling the dump.

Fourth, to provide an improved hydraulic control for the scraper in which the liquid, oil, is forced into the cylinder and by its pressure maintains the scraper fixedly in place.

Fifth, to provide improved means of relieving and adjusting the pressure on such a hydraulic control.

Sixth, to provide improved detailed construction for the attachment and support of a hydraulic cylinder.

Seventh, to provide improved spring actuating connections to cooperate with such hydraulic control.

Further objects and objects pertaining to details and economies of my construction will definitely appear from the description to follow.

I accomplish the objects of my invention by the devices and means described in the following specification. The invention is clearly defined and pointed out in the claims.

A device embodying my invention is clearly illustrated in the accompanying drawings forming a part of this specification, in which:

Fig. 1 is a detail side elevation view of a portion of the chassis or body of a truck with my improved scraper means in position, portions of the truck being broken away and other portions being indicated by dotted lines.

The same is there illustrated to take hydraulic power from the pump means provided for hydraulic dump.

Fig. 2 is a detailed diagrammatic plan view reduced, of the hydraulic connections and actuating means as they appear in Fig. 1, the return springs and scraper supporting beam being omitted.

Fig. 3 is an enlarged detailed perspective view of the hydraulic cylinder and its connections, parts being shown broken away.

Fig. 4 is an enlarged detailed vertical longitudinal sectional view taken on section line 4-4 of Figs. 2, 3 and 9, through the center of the power cylinder, portions being shown in full lines and the arrangement of one of 55 the return springs being indicated.

Fig. 5 is a detailed sectional elevation taken on line 5-5 of Figs. 1, 2 and 9 showing the relation of the spring supported scraper to the hydraulic cylinder scraper supporting 60 beam and other parts.

Fig. 6 is an enlarged detailed sectional view taken on line 6-6 of Fig. 1, a part of one turn of the spring being shown to indicate its operative relation. 65

Fig. 7 is an enlarged detail vertical longitudinal section on line 7-7 of Figs. 2 and 9 showing details of the pressure control.

Fig. 8 is an enlarged detailed vertical sectional elevation through the rotary pump and 70 its valve taken on section line 8-8 of Figs. 1 and 2 showing the by-pass control to permit the spring return of the scraper.

Fig. 9 is a plan view of my invention as operated and controlled by a hand pump. 75

Fig. 10 is a detailed sectional elevation on line 10-10 of Fig. 9 showing details of construction and arrangement.

The parts will be identified by their numerals of reference which are the same in all 80 views.

1 is the truck chassis frame. 2 is the cab. 3 is the scraper supporting beam carried by adjustable supports or brackets 4 bolted at 41 41 to chassis frame 1, and having curved segments 42 on which the scraper beam 3 is carried adjustably by the clamps 44, the construction being identical on both sides of the chassis. 85

The scraper might be supported without 90 adjustment but the hydraulic control permits very ready adjustment and is of advantage in that relation.

The scraper supporting beam 3 is provided with brackets 31 31 distributed along its 95 length in which is supported the scraper rock-shaft 5. The scraper 6 is carried by a series of C-shaped blade springs 7, preferably reinforced as indicated. Centrally of the rock shaft 5 are arms 51 for connection 100

of the hydraulic means. 8 is the hydraulic cylinder secured to the beam 3 preferably by a pair of U-shaped bolts 81. The head of the cylinder 82 is of heavy casting and notched to accommodate one of the flanges of the scraper supporting beam 3. The hydraulic cylinder is provided with the usual hydraulic piston 83 with a plunger rod 84 and with a return spring 85.

10 A cross head 86 is secured to the plunger rod 84 and is provided with projecting pivots 87.

Connecting links 52 connect the cross head to the actuating arms 51 of the rock shaft 5.

15 Cross arm 9 with up-turned ends 91 provides connection for the return springs 92 which are connected at the opposite end to brackets 93 on the scraper supporting beam 3. These springs may provide the entire 20 power for returning the piston and elevating the scraper or the spring 85 may perform this function. Also to facilitate this action coiled springs 10 may be interposed between an abutment collar on bracket 31 and an 25 adjustable collar 101 on the shaft 5, the same being adjustably secured in place by set-screw 102, see Fig. 6.

There is considerable weight to the scraper structure and it seems best to provide a series 30 of springs in the manner indicated to insure even and steady control, while it is equally clear that any one of the sets of springs referred to, if made sufficiently strong, would do the work.

35 Where the truck to which my improved scraper is to be secured is provided with a hydraulic dump, I preferably use the hydraulic means there provided for actuating the hydraulic cylinder and controlling the 40 scraper. To accomplish this I provide the connection 11 12 to the hydraulic pump 13. The hydraulic pump 13 is driven from what is known as a take-off 14 on the transmission 45 gear 15 of the truck. A 3-way valve 16 is provided for cutting off the hydraulic control of the dump 17 when the hydraulic scraper control is utilized.

The pressure is then delivered from the 50 pump 13 to the end of the hydraulic cylinder past the specially constructed control check valve 18. There is a conical valve 19 seating in the seat 181 of the valve. This valve 19 is perforated longitudinally at 191. A 55 plunger rod 20 with longitudinal grooves 201 adapted to adjust in the longitudinal bore 191 is provided for relieving the heavy pressure when it is desired to regulate the pressure in the hydraulic cylinder.

60 Valve 19 is provided with a guiding stem 192 which extends into a guiding recess 183 in the screw cap 283 of the casing of valve 18. The guiding stem 192 is longitudinally grooved to permit the free movement thereof 65 in the recess. This screw cap is of sufficient

dimension to permit the introduction of the valve 19.

A stuffing box 202 is provided for the plunger rod 20. The plunger rod is controlled from the cab by the driver. This 70 control consists of a yoke 203 which is pivoted to the control lever 204 which is fulcrumed on bracket 184 on the casing of valve 18, see Fig. 7 where part of the yoke is broken away and is cross sectioned below the 75 plunger 20.

A spring 205 connects this lever to the casing and returns the same. Connection 206 is provided with a ring or handle 207 in the 80 cab 2.

It will thus be seen that no matter how strong the pressure, which may be two or three hundred pounds to the square inch, it will be perfectly easy for the operator to relieve that pressure and, if he wishes to 85 completely raise his scraper, it is only necessary for him to pull on the handle 207 which at once through connection 206 and yoke 203 raises plunger 20, and relieves the pressure on the valve 19 through the grooves 201 in 90 the said plunger rod 20 when the whole valve disk 19 can be easily raised and the return springs will force the hydraulic piston 83 inward and raise the scraper.

95 Of course to do this it is necessary to bypass the pump and this is done by controlling the by-pass valve 131 of the pump 13 (see Fig. 8). This is done through the connection to the by-pass control lever 132 by the connection 133, the same comprising the 100 necessary rods, links and levers as indicated.

The power take-off 14 is the same as that used for the dump and is controlled by the control lever 142 which is provided with connections 143 for that purpose, the same being 105 the usual connection for such take-off and not necessary to detail here.

I provide a pressure gauge 21 which may be connected to the hydraulic cylinder or any other part subjected to the pressure, and enables the operator to regulate the control of the force that he will apply to the scraper and this can be regulated to anything within the capacity or load of the truck or frame 110 to which the hydraulic scraper structure is attached.

Where a truck with a hydraulic control on it is not available, I provide the structure as indicated in the Figs. 9 and 10. I here place a hydraulic pump 22, an inch plunger 120 being sufficiently large, with a lever pump handle 221 which I connect to the delivery pipe connection 11 to the hydraulic cylinder.

An oil reservoir 23 is disposed preferably under the seat of the cab which delivers 125 through pipe 231 to the pump. I provide a by-pass 232 with a globe valve 233 to permit the return of oil from the hydraulic power cylinder to the reservoir 23 through pipes 11 and 231.

When the valve is closed, of course, the pump, a crosshead for the said hydraulic cylinder, link connections therefrom to the actuating arms of the rockshaft, and spring return means for the rockshaft, coacting as specified.

5 I have thus described my invention in its adaptations to the power plant and also to a hand operated pump. The hydraulic control as here shown is of great importance. The oil, when enclosed in the cylinder, is 10 practically incompressible and holds the scraper fixedly in place. By this means worm gears, pinions and lock levers in common use are avoided and the waste of the great friction from the use of such devices is eliminated. The action of this hydraulic means 15 is easy because of the use of oil which, of course, is a lubricant and its action in the cylinder is easy and quick with a minimum of friction. In the manipulation of a structure of this kind this advantage is of great importance.

I have described the structure as self-contained as an attachment to a truck. This is of very great advantage in such a structure but, of course, can be made use of in various ways.

I desire to claim the invention specifically as shown and also broadly as pointed out in the appended claims.

30 Having thus described my invention, what I claim as new and desire to secure by Letters Patent, is:

1. In a scraper structure, the combination with a truck chassis having a power transmission, a power take-off therefor with control extended to the cab of the truck, a pump with a valved by-pass to permit return of the oil with control extended to said cab, a scraper structure comprising a supporting beam adjustably attached to the said truck chassis, supporting brackets on said beam, a scraper, a rockshaft, spring arms from the said rockshaft to the said scraper, actuating arms on the rockshaft, a hydraulic power cylinder secured to said scraper supporting beam with connections to the power pump, a three-way cock for directing the oil to the said hydraulic cylinder, a crosshead for the said hydraulic cylinder, link connections 45 therefrom to the actuating arms of the rockshaft, return spring means for said scraper, a control check valve with a regulating plunger rod therethrough, and connections 50 therefrom to the cab to control the pressure 55 in said cylinder.

2. In a scraper structure, the combination with a truck chassis, a power hydraulic pump, a scraper structure comprising a supporting beam attached to said chassis, sup- 60 porting brackets on said beam, a scraper, a rockshaft pivoted in said brackets, spring arms from the said rockshaft to the said scraper, actuating arms on the rockshaft, a hydraulic power cylinder secured to said beam with connections to the said power

70

3. In a scraper structure, the combination with a truck chassis, a power hydraulic pump, a scraper structure comprising a supporting beam attached to said chassis, supporting brackets on said beam, a scraper, a rockshaft pivoted in said brackets, spring arms from the said rockshaft to the said scraper, actuating arms on the rockshaft, a hydraulic power cylinder secured to said beam with connections to the said power pump, a crosshead for the said hydraulic cylinder, link connections therefrom to the actuating arms of the rockshaft, coacting as specified.

75

4. In a scraper structure, the combination with a truck chassis, a hydraulic pump, a scraper structure comprising a supporting beam attached to said chassis, supporting brackets on said beam, a scraper, a rockshaft pivoted in said brackets, spring arms from the said rockshaft to the said scraper, actuating arms on the rockshaft, a hydraulic power cylinder secured to said beam with connections to the said pump, a crosshead for the said hydraulic cylinder, link connections 80 therefrom to the actuating arms of the rockshaft to hold them by the hydraulic pressure, coacting as specified.

85

5. In a scraper structure the combination of an adjustable supporting beam, a scraper, supporting brackets therefor, a rockshaft, spring arms from said rockshaft to said scraper, a hydraulic cylinder mounted on said supporting beam with suitable controls connected to said rockshaft to actuate the same and to apply pressure to said scraper 90 and hold it by hydraulic pressure as specified.

100

6. In a scraper structure the combination of an adjustable supporting beam, a scraper, supporting brackets therefor, a rockshaft, arms from said rockshaft to said scraper, a hydraulic cylinder with suitable controls mounted on said supporting beam and connected to said rockshaft to actuate the same and to apply pressure to said scraper and hold 105 it by hydraulic pressure as specified.

110

7. A scraper structure comprising the combination of an adjustable supporting beam, a scraper with pivotal supports therefor, and a hydraulic cylinder mounted on said supporting beam connected to actuate and control said scraper and hold it by hydraulic pressure as specified.

115

8. In a scraper structure the combination of a scraper, a hydraulic cylinder for controlling same, spring returns for the said scraper, a check valve for the supply to said hydraulic cylinder, a relief valve disposed through the said check valve, a yoke and lever connection for said relief valve to ac- 120

tuate same to release pressure and raise check valve as specified.

9. In a scraper structure, the combination of an adjustable supporting beam, a scraper, supporting brackets therefor, a rockshaft, arms from said rockshaft to said scraper, a hydraulic cylinder with suitable controls mounted on said supporting beam and connected to said rockshaft to actuate the same 10 and to apply pressure to said scraper and hold it by hydraulic pressure, and a spring return means for said scraper.

10. A scraper structure comprising the combination of an adjustable supporting beam, a scraper with pivotal supports therefor, and a hydraulic cylinder mounted on said supporting beam connected to actuate and control said scraper and hold it by hydraulic pressure, and spring return means 20 for said scraper.

11. In a scraper structure, the combination of a supporting beam, a scraper, supporting brackets therefor, a rockshaft, arms from said rockshaft to said scraper, a power cylinder mounted on said supporting beam with suitable controls, a piston within said cylinder connected to said rockshaft to actuate the same and to apply pressure to said scraper and hold it to its work.

12. A scraper structure comprising the combination of an adjustable beam, a scraper with pivotal supports therefor, a power cylinder mounted on said supporting beam, and a piston within said cylinder connected to 35 actuate and control said scraper and hold it to its work.

13. A scraper structure comprising the combination of an adjustable beam, a scraper with pivotal supports therefor, a power cylinder mounted on said supporting beam, a piston within said cylinder connected to actuate and control said scraper and hold it to its work, and spring return means for 40 said scraper.

14. In a scraper structure, the combination with a truck chassis, a pump carried thereby, a scraper structure comprising a supporting beam attached to and supported beneath said chassis, brackets on said beam, a rockshaft in said brackets, a scraper carried by said rockshaft, spring arms from said rockshaft to said scraper, actuating arms on said rockshaft, a power cylinder with piston between said beam and scraper, connections 50 therefrom to actuate the arms of the rockshaft to apply pressure to said scraper and hold it to its work, flexible connections from said power cylinder to said pump, and spring return means for said scraper.

15. In a scraper structure, the combination with a truck chassis, of a scraper structure comprising a supporting beam attached to and supported beneath said chassis, brackets on said beam, a rockshaft in said brackets, a 60 scraper carried by said rockshaft, spring

arms from said rockshaft to said scraper, actuating arms on said rockshaft, a power cylinder with piston between said beam and scraper, connections therefrom to actuate the arms of the rockshaft to apply pressure to said scraper and hold it to its work, spring return means for said scraper, and means for delivering fluid under pressure to said cylinder.

16. In a scraper structure, the combination with a truck chassis, of a scraper structure comprising a supporting beam attached to and supported beneath said chassis, brackets on said beam, a rockshaft in said brackets, a scraper carried by said rockshaft, actuating arms on said rockshaft, a power cylinder with piston between said beam and scraper, connections therefrom to actuate the arms of the rockshaft to apply pressure to said scraper and hold it to its work, spring return means for said scraper, and means for delivering fluid under pressure to said cylinder.

17. In a scraper structure, the combination with a truck chassis, a scraper structure comprising a supporting beam attached to and supported beneath said chassis, brackets on said beam, a rockshaft in said brackets, a scraper carried by said rockshaft, actuating arms on said rockshaft, a power cylinder with piston between said beam and scraper, connections therefrom to actuate the arms of the rockshaft to apply pressure to said scraper and hold it to its work, and means for delivering fluid under pressure to said cylinder.

18. In a scraper structure, the combination with a truck chassis, of a scraper structure comprising a supporting beam attached to and supported beneath said chassis, brackets on said beam, a rockshaft in said brackets, a scraper carried by said rockshaft, actuating arms on said rockshaft, a power cylinder with piston between said beam and scraper, connections therefrom to actuate the arms of the rockshaft to apply pressure to said scraper and hold it to its work, means for delivering fluid under pressure to said cylinder, and spring means to elevate said scraper.

19. In a scraper structure, the combination with a truck chassis, of a scraper structure comprising a supporting beam attached to and supported beneath said chassis, brackets on said beam, a rockshaft in said brackets, a scraper carried by said rockshaft, actuating arms on said rockshaft, a power cylinder with piston between said beam and scraper, connections therefrom to actuate the arms of the rockshaft to apply pressure to said scraper and hold it to its work, and means for delivering fluid under pressure to said cylinder.

In witness whereof I have hereunto set my hand.

ERNEST A. WEEKS.
